UNITED STATES PATENT OFFICE.

JOSEPH G. CROSS, OF EVERETT, WASHINGTON.

RAILWAY CATTLE-GUARD.

1,161,113.

Specification of Letters Patent.

Patented Nov. 23, 1915.

Application filed June 1, 1915. Serial No. 31,390.

To all whom it may concern:

Be it known that I, JOSEPH G. CROSS, a citizen of the United States, residing at Everett, in the county of Snohomish, State 5 of Washington, have invented a new and useful Improvement in Railway Cattle-Guards, of which the following is a specification.

My invention relates to railway cattle guards, of the type employing a hinged gate member extending across the track, which is normally raised, and is depressed by the passage of a train.

The object of my invention is to provide 15 a cattle guard which will extend across the track, which will be of sufficient height to prevent the passage of cattle, and which will be lowered automatically by the train to permit its passage.

20 My invention comprises the novel parts and combinations of parts which are herein illustrated in the accompanying drawings, described in the specification, and more particularly defined in the claims.

25 In the accompanying drawings I have shown my invention in its present most preferred form.

Figure 1 is a plan view of my gate and the operating mechanism, a part thereof being 30 broken away. Fig. 2 is a longitudinal section taken approximately half-way between the rails. Fig. 3 is a transverse section through my device, taken on the center line of the gate. Fig. 4 is a section through the 35 railway rail and the operating bar of my device, showing the manner of pivoting said bar.

My device is of that class of cattle guards which employs a gate extending transversely 40 of the track, and pivoted at its lower edge so as to permit its depression while a train is passing and which is automatically raised after the passage of the train. A shaft 1 extends transversely of and beneath the rails 45 2, and to any distance at each side thereof. Shaft 1 is pivoted in suitable bearings 10. A plurality of gate members, herein shown as rods 11, are secured to the shaft 1 in any suitable manner, and normally extend upward to prevent the passage of cattle.

Operating bars 3, preferably formed as angle bars, are pivoted close along the inner sides of the rails and extend lengthwise thereof. This bar 3 may be pivoted to the 55 rail 2, or to the tie, as may be desired, its pivot axis extending in the same direction as

the rail and the bar itself. As shown, small castings 4 are secured upon the inside of bar 3, at suitable intervals, and are provided with pivot ears 41. Other castings 21 are secured to the rail 2 by bolts 22, and the castings 4 are pivoted therein at 23. These pivot points 23 should, preferably, be as close to the angle of the bar as possible, and should be far enough from the rail 2 to be outside 60 of the path of the flanges on the wheels of a train, as shown in Fig. 3. Bar 3 is thus pivoted so that one flange, 30, is in a horizontal plane, and at about the level of the rail tread, while the other flange, 31, being 65 longer and heavier than flange 30, hangs vertically downward. The tendency of such a bar when pivoted in this manner, is to swing the lower flange under the pivot. The weight of the bars 3 is sufficient to turn the 70 gate and hold it in raised position. Flange 30 should extend close to rail 2, and is engaged and depressed by the flange on the wheels to operate the gate-lowering mechanism, as will be later described. 75

A link 5 is pivoted by one end to bar 3, preferably as low as possible thereon, as at 51, and at its other end is pivoted to a bell-crank lever 52. Bell-crank lever 52 is pivoted to the tie at 53. A crank arm 54 is secured to the shaft 1, as by set screw 55, and a link 56 is pivoted thereto. Link 56 is pivoted at its other end to the bell-crank lever 52. This link 56 is preferably formed in two parts, connected by a turnbuckle 57, whereby 80 adjustment to get exact length or to take up slack in the mechanism may be secured. 85

When the flange 30 of operating bar 3 is depressed by engagement therewith of the flange on the wheel of a train, it imparts a 95 movement to the crank arm 54, through links 5 and 56 and bell-crank lever 52. This turns shaft 1 and the gate members are depressed, and lie horizontally along the ties, As the shaft 1 is beneath the level of the ties, 100 the gate members 11 are offset slightly, as at 12, as shown in Fig. 2, to permit of their lying flat. The position of the parts while a train is passing is shown by dotted lines in Fig. 1. 105

It is desirable that there be operative links and levers as described above, at each side of the shaft 1 so that the movement of the gate up or down will be actuated by a pull upon links 56 rather than a push, as would 110 be the case at times if there were only one set. I have also shown a second complete

set of operating members upon the opposite side of the track, and actuated by a second operating bar 3, secured to the opposite rail. It is obvious, however, that one of these operating bars 3, with its associated mechanism, would be sufficient to operate the gate, though I prefer to use two sets. These bars 3 may also extend to any convenient distance along the track from the gate members 11, and the ends thereof should be far enough away to give the gate time to come to rest upon the ties before the train passes over it.

I claim as my invention—

- 15 1. A railway cattle guard comprising a pivoted gate bar, gate members secured thereto and normally held in vertical position, an operating bar pivoted to the railway rail and lying close alongside thereof with its pivot axis extending in the same direction as the rail, and adapted to be depressed by a train, a link pivoted at one end to said operating bar and at its other end to a bell-crank lever, a bell-crank lever, a crank arm secured upon said pivoted gate bar, and a second link pivoted at one end to said crank arm, and at its other end to said bell-crank lever, whereby said gate members may be swung to a horizontal position during the 30 passage of a train.
- 20 2. A railway cattle guard comprising a pivoted gate bar, gate members secured thereto and normally held in vertical position, an operating bar pivoted to the railway rail and lying close alongside thereof, and adapted to be depressed by the flange on the wheels of a passing train, said pivot points being inside of the path of said flanges, and extending in the same direction as the rail, a 35 link pivoted at one end to said operating bar and at its other end to a bell-crank lever, a bell-crank lever, a crank arm secured upon said pivoted gate bar, and a second link pivoted at one end to said crank arm and at its 40 other end to said bell-crank lever, whereby said gate members may be swung to horizontal position during the passage of a train.
- 25 3. A railway cattle guard comprising a pivoted gate bar, gate members secured thereto and normally held in vertical position, an operating bar pivoted to the railway rail and close alongside thereof, with its pivot axis extending lengthwise of and in the same direction as the rail, and adapted

to be depressed by the flange on the wheels 55 of a train, said pivot points being inside the path of said flanges, a flange depending from said operating bar and adapted to hold said bar in raised position, a link pivoted at one end to said flange at a point lower than said 60 first pivot points, and at its other end to a bell-crank lever, a bell-crank lever, a crank arm secured upon said pivoted gate bar, a second link composed of two separate parts pivoted at one end to said crank arm and at 65 its other end to said bell-crank lever, and a turnbuckle connecting the ends of said second link, whereby said gate members may be swung to horizontal position during the passage of a train.

70 4. A railway cattle guard comprising a gate having a pivot axis extending beneath and transversely of the rails and adapted to be turned to bring its elevated parts into substantially horizontal position, angle bars 75 extending lengthwise of and inside the rails with one flange occupying a substantially horizontal plane close inside of and at approximately the level of the rail tread, the other flange extending downward from the 80 inner edge of the first named flange, said angle bars being pivoted upon axes extending lengthwise thereof and closely adjacent the apex of the angle between the flanges, and operative members connecting the depending flange with the pivoted gate to depress the gate when the free edge of the horizontal flange is depressed by the wheel flanges.

85 5. A railway cattle guard comprising a pivot shaft extending transversely of and beneath the railway rail, gate members secured to said shaft and containing an offset angle near the shaft, whereby they may be turned into horizontal positions which are 90 below the level of the rail treads, angle bars mounted on pivots which extend lengthwise said bars and the rails, in position to have the outer edge of one flange engaged and depressed by the wheel flanges, operating connections between said angle bars and the gate, the pivot axis of said angle bars being so disposed that the weight of the angle bar acts to normally maintain the gate and the flange which is depressed by the wheel 105 flanges, in raised positions.

JOSEPH G. CROSS.
